UNITED STATES PATENT OFFICE.

WILLIAM O. CAMPBELL, OF NEW YORK, N. Y.

DESIGN FOR A DISH-DRAINER.

SPECIFICATION forming part of Design No. 26,850, dated March 30, 1897.

Application filed February 12, 1897. Serial No. 623,194. Term of patent 7 years.

To all whom it may concern:

Be it known that I, WILLIAM O. CAMPBELL, a citizen of the United States, residing at New York city, in the county and State of New York, have invented and produced a new and original Design for a Dish-Drainer, of which the following is a specification, reference being had to the accompanying drawings, forming a part thereof, in which—

Figure 1 is a plan view of a dish-drainer embodying the features of my design, and Fig. 2 is a longitudinal central section on the line 2 2 in Fig. 1.

The main feature of the design consists in a tapering body A, a tapering spout B, and a barrier C in the body near the spout.

The details of the formation of the main parts of the dish-drainer constitute a further feature of the design, namely: The sides of the bottom a of the body converge, and the contracted end of the bottom is given a down-

ward and an outward inclination, forming an extension which constitutes the bottom b of the spout. The sides of the spout converge, its lower end being narrowest. An upwardly-extending flange d is located at the wide end and the sides of the bottom of the body. The sides of the bottom of the spout are also provided with flanges d', connecting with those constituting the sides of the body. The barrier C has the appearance of a rod resting at its ends in sockets e on the sides of the body. A handle D is placed upon the rear body-flange and a foot E is located upon the under side of the bottom of the body. 30 35 25 20

I claim—

The design for a dish-drainer herein shown and described.

WILLIAM O. CAMPBELL.
